UNITED STATES PATENT OFFICE.

HJALMAR EMANUEL ANDERSSON, OF STOCKHOLM, SWEDEN.

ELECTRIC CLOCK.

SPECIFICATION forming part of Letters Patent No. 638,160, dated November 28, 1899.

Application filed February 16, 1899. Serial No. 705,711. (No model.)

To all whom it may concern:

Be it known that I, HJALMAR EMANUEL ANDERSSON, clock and watch maker, of Stockholm, Sweden, have invented certain new and useful Improvements in Electrical Clock-work; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

My invention has relation to clocks; and it has for its object the provision of means for periodically and automatically winding up the motor-spring for the time mechanism.

It has for its further object the provision of means for electrically operating the striking-appliances, and thereby dispensing with the spring usually employed for the striking-train, the electrical appliances for operating the striking mechanism serving at the same time as a means for periodically winding up the motor-spring for the time mechanism, so that a comparatively short spring can be used and compactly arranged in the clock-framing, said spring occupying an exceedingly small space as compared with the space required for the usual striking-train spring.

The invention has for its further object a construction whereby the clock mechanism is materially simplified; and, finally, my said invention has for its object certain improvements in parts of the clock mechanism, whereby their construction is materially simplified and their efficiency increased.

That my invention may be fully understood, I will describe the same in detail, reference being had to the accompanying drawings, in which—

Figure 1 is a front elevation of a clock mechanism constructed and organized for operation in accordance with my invention. Fig. 2 is an elevation thereof, showing the mechanism in rear of the forward frame-plate, which latter is removed, together with the mechanism in front thereof. Fig. 3 is a rear elevation of the mechanism arranged in front of the forward frame-plate. Fig. 4 is a rear elevation of the clock mechanism, the vertical arm or extension of the console or bracket

which is designed to support said mechanism and to be secured to the clock-casing being shown in dotted lines. Figs. 5 and 6 are opposite side elevations. Figs. 7 and 8 are detail views. Fig. 9 is a vertical section of the circuit-breaker; and Fig. 10, a cross-section thereof on line A B of Fig. 9, just above the circuit-breaker proper. Fig. 11 is a detail perspective view of the hammer-operating mechanism and the appliances for controlling the operations thereof, the lower portion of the lever 40 being broken off to more clearly show the contact-plate 54, and for the sake of clearness the clock-frame plates 3 and 4 are omitted. Fig. 12 is a fragmentary top plan view of the mechanism shown in Fig. 11, the clock-frame plates 3 and 4 being shown in dotted lines; and Fig. 13 is a sectional view drawn to an enlarged scale and taken about on line a b of Fig. 1.

In the mechanically and electrically operated clock to be described there is a circuit maker and breaker in the primary circuit of an electromagnet and in a normally-closed relation to said circuit, said circuit maker and breaker being controlled by the armature of the electromagnet, and in said circuit is also included a circuit-closer controlled by the escapement to close the main circuit through the electromagnet and circuit-breaker at each revolution of the escapement-wheel, thereby oscillating the armature in one direction to partly wind up the motor-spring of the time-train through intermediate mechanism and at the same time interrupt the main circuit, for purposes hereinafter described, the armature swinging back to a normal position and at the same time reopening the main circuit through the circuit-breaker. There is a third circuit-closer in a branch or shunt from the main circuit, operated by the let-off cam of the striking mechanism, for purposes hereinafter set forth, and a fourth circuit-closer in a shunt from the main circuit for maintaining said circuit and the first-mentioned shunt-circuit closed when the striking-mechanism-circuit closer opens the circuit, for purposes to be described. Now in order to distinguish these circuit-making and breaking devices other than by reference-symbols, and particularly in the claims, I will refer to the first-named device as the "pri-

mary-circuit" breaker, to the second as the "time-circuit" closer, to the third as the "striking-circuit" closer, and to the fourth as the "auxiliary-circuit" closer.

5 The clock mechanism is carried, as usual, by two frame-plates 3 and 4, which will hereinafter be referred to as the "forward" and "rear" frame-plates, respectively, said plates being secured together, as usual, by spacing-
10 pillars 3^a, and said frame is secured to the horizontal arms 74^a of a console or bracket 74 by means of screws 61. To the vertical arm or extension 74^b of the bracket 74 is secured a gong, or, as shown in Fig. 4, a sounding-
15 spring 60. The frame-plates 3 and 4 have the form of an inverted T—that is to say, they have an upper portion the diameter of which is considerably less than that of the lower portion of said plates. To the upper edge of
20 the forward frame-plate 3 is secured a cross-piece 75, which carries two electromagnets 1 and 1^a, one on each side of the narrower upper portion of said frame-plate, the pole-shoes of
25 which electromagnets are likewise secured to the wider portion of said plate by means of screws 76, Fig. 1. Between the two electromagnets 1 and 1^a and supported in a ring or rings secured to frame-plate 3 is arranged the primary-circuit breaker, which may be of any
30 well-known construction. I prefer, however, to use the circuit-breaker 17, (shown in Figs. 1, 9, and 10,) which consists of a vessel 17^a, preferably cylindrical and made of glass, of
35 two glass tubes 17^b, secured fluid-tight in the heads of the vessel, so as to leave a narrow slit between them within said vessel, and of an arbor 17^d, stepped in the latter and projecting through its upper head and carrying at its outer end a bifurcated lever 32, whose arms
40 32^a and 32^b are acted upon by an armature, said shaft also carrying a cut-off 30 in the form of a thin plate of insulating material, preferably of mica, so located on the arbor
45 17^d as that when the latter is rocked in one direction the cut-off 30 will interrupt the continuity of a body of mercury 17^c in tubes 17^b, so as to break the electrical connection between the leads 16 and 18 and to reestablish said connection when arbor 17^d is rocked in
50 an opposite direction. The described circuit-breaker is fully shown and described in Letters Patent of the United States granted to me April 11, 1899, No. 622,657, and its advantages are therein fully set forth and need
55 therefore no further reference herein.

As shown at Fig. 1, the pole-shoes 1^b and 1^c of the electromagnets 1 and 1^a, respectively, are extended downward and have a concave recess in their proximate faces, and on an
60 arbor 5 is loosely mounted an armature 2, having sector-shaped arms 2^a and 2^b, the latter arm carrying a weight 34 for the purpose of returning the armature into a normal position after being attracted by the poles of
65 the electromagnets 1 and 1^a on the closure of an electric circuit and its subsequent interruption. To the arm 2^a of the armature 2 is

secured a rod 33, that extends through an oblong opening in the forward frame-plate 3, with its free end between the arms 32^a and 32^b of the bifurcated lever 32 on the arbor 17^d of the circuit-breaker 17, Fig. 1, and said armature-arm 2^a also carries a pawl 27. As stated, the armature 2 is loosely mounted on an arbor 5, which has secured to its forward end, in front of forward frame-plate 3, a pinion 48, Fig. 1, and to its rear end, back of the rear frame-plate 4, a hammer-actuating disk 50, having hammer-lifting pins projecting from its front face. As shown in Figs. 2 and 7, the arbor 5 has, furthermore, secured thereto, between the armature 2 and the back of the forward frame-plate 3, a ratchet-wheel 28, engaged by the aforesaid pawl 27 on the arm 2^a of said armature and by a check-pawl 29, 85 carried by said frame-plate. On arbor 5, back of the armature 2, is loosely mounted a barrel 21, to the forward end of which is secured a ratchet-wheel 25, which in practice may be formed integral with said barrel, as shown in Fig. 7, engaged by a check-pawl 26 on a cross-rod 26^a. In rear of the barrel 21 are loosely mounted on said arbor 5 a gear-wheel 22 and a pinion 22^a, which is preferably formed integral with wheel 22. The latter 95 wheel gears with a pinion 22^b on the arbor 6, which carries the escapement-wheel 8, and the pinion 22^a meshes with a gear-wheel 22^c on the arbor 64, which carries the usual hour and minute hand sleeves. 100

The anchor 9, which controls the escapement-wheel, is secured to an arbor 7, that receives its oscillating movements from a pendulum 65 in the usual manner, said arbor 7 also carrying a conductive sleeve 12, insulated therefrom and having secured thereto two contact-springs 11, that project into the path of a contact-pin 10, projecting from the rear face of the escapement-wheel 8 and constituting the time-circuit closer. 110

On the aforementioned barrel 21, as shown in Fig. 7, is wound the motor-spring 20 for the time mechanism, one end of said spring being secured to the forward end of said barrel and the other to the gear-wheel 22. Within the barrel 21 the arbor 5 has a circular flange or collar 5^a, which forms an abutment for a disk 23, between which and the opposite end of the barrel is arranged a spring 24, coiled about the arbor, the power of which spring is sufficiently great to lock the barrel to the arbor by frictional resistance during the winding up of the motor-spring 20, which frictional resistance is, however, overcome whenever said motor-spring is wound up to excess, thus allowing the arbor 5 to revolve independently of said barrel, so that a breakage of the motor-spring is effectually guarded against. 120

From the described arrangement of motor-spring and in view of the fact that said spring drives the time mechanism only it will be seen that a comparatively short spring, taking up but very little space, can be made use of. 130

In the normal position of the armature 2—that is to say, in the position it occupies when the electromagnets are demagnetized—the arm 33 on armature-arm 2^a holds the arm 32^a on arbor 17^d of the circuit-breaker 17 in such a position that the cut-off 30 will not interrupt the continuity of the column of mercury 17^c in the tubes 17^b thereof.

The sleeve 12, hereinabove referred to, on the arbor 7, which carries the anchor of the escapement-wheel, is included in the circuit of a suitable electric generator, as a battery 13, (diagrammatically illustrated in Figs. 1, 2, and 4), in which circuit are also included the electromagnets 1 and 1^a and the terminals 16 and 18 of the described circuit-breaker.

The electric circuit is normally open, but normally closed through the circuit-breaker 17, and as the escapement-wheel 8 rotates and its contact-pin makes contact with the springs 11 on sleeve 12 on the anchor-arbor 7 the electric circuit will be closed, current flowing from battery 13 through wire 14, electromagnet 1, wire 15, electromagnet 1^a, wire 16, column of mercury 17^c of circuit-breaker 17, wire 18, clock-frame, escapement-wheel arbor 6, escapement-wheel 8, its contact-pin 10, contact-springs 11 of sleeve 12 on anchor-arbor 7, and wire 19 back to battery 13.

The closure of the electric circuit produces the following results, to wit: The armature 2 is attracted, and thereby caused to make a partial revolution on arbor 5, which is transmitted, through the pawl 27 on armature-arm 2^a, to the winding-ratchet 28, and as the barrel 21 is locked to the arbor 5 by the described friction-clutch said barrel will revolve with said arbor, and in view of the fact that one end of the motor-spring 20 is secured to the barrel 21 and the other end of said spring to the gear 22 the spring will be partly wound up, which operation, as will be readily understood, takes place at each complete revolution of the escapement-wheel 8.

The distance between the arms 32^a and 32^b of the bifurcated lever 32 on the cut-off arbor 17^d of the circuit-breaker 17 is such that as the armature is rocked magnetically on the closure of the electric circuit, as above described, the arm 33 on the arm 2^a of said armature will impinge upon the arm 32^b of said lever 32 and turn the cut-off arbor 17^d of the circuit-breaker 17, so as to move the cut-off 30 in the space between the two tubes 17^b and destroy the continuity of the column of mercury in said tubes, and thereby interrupt or open the electric circuit, the arrangement being such that this will take place a little before the contact 10 moves clear of the contact-springs 11.

The opening of the circuit has for its result the demagnetization of the electromagnets, the return of the armature 2 under the action of its weight 34 into its normal position, and the closure of the electric circuit through the circuit-breaker 17 by the action of the rod 33 on the armature-arm 2^a on the

arm 32^a of the bifurcated lever 32 on cut-off arbor 17^d, whereby the latter is turned and the cut-off 30 moved to restore the continuity of the column of mercury 17^c in the tubes 17^b of the circuit-breaker 17.

As is well known, the armature of an electromagnet receives a very sudden impulse whenever said electromagnet is energized, and to obviate sudden shocks on the arms 32^a and 32^b of the cut-off arbor 17^d of the circuit-breaker I secure to the hub of the armature a radial arm terminating in a toothed sector 37 in gear with a pinion 38^b on an arbor 38^a, carrying a governor or fly 38, Figs. 2, 4, and 5.

One of the important points of my invention lies in the form of the anchor-pallets, so as to reduce the contacting surfaces between said pallets and the teeth on the escapement-wheel to a minimum, and thereby correspondingly minimize the frictional resistance in order to avoid a stoppage of the escapement-wheel when the pin 10 thereon is in contact with the springs 11 on sleeve 12 and the electric circuit is closed. To this end I construct the anchor-pallets in the form of arcs of a circle, having for center the axis of oscillation of the anchor 9, as shown in Fig. 8, so that the forward face of one escapement-tooth 36 will have bearing on the concave face of one of the pallets 35, and as the latter swings out and the pallet 35^a swings in to engage another tooth 36^a on the escapement-wheel the forward face of the latter will have bearing on the convex face of said pallet 35^a. Furthermore, the teeth on the escapement-wheel 8, as more clearly shown in Fig. 8, have their outer faces inclined in a direction opposite to the direction of rotation of said wheel, while the body of the teeth is made tapering inwardly, so that the contact between teeth and pallet is a mere line—namely, at the opposite edges of the beveled faces of the teeth. Furthermore, the contact-pin 10 and contact-springs 11 are so arranged as to make contact at the moment when a pallet of the anchor engages a tooth on the escapement-wheel—that is to say, during the momentary stop of the escapement-wheel, Fig. 8—thus insuring a perfect contact and closure of the electric circuit, inasmuch as the contact-pin 10 remains in contact with the springs 11 for a certain length of time, although this is very short, yet sufficiently long to engender magnetic resistance at the contacts on the closure of the electric circuit, and to minimize this resistance the electric circuit is opened, as hereinabove stated, before said contacts move clear of each other and at the moment an anchor-pallet moves out of contact with a tooth on the escapement-wheel, so that a stoppage of the latter cannot occur.

The striking mechanism is operated electrically. Hence the spring usually employed for driving the striking-train is dispensed with.

The arbor 64, as shown in Figs. 1 and 3, carries at its forward end, in front of the forward

frame-plate 3, the usual minute and hour hand sleeves, and to the former is secured a pinion 66, meshing with a pinion 67 on an arbor 68, which carries a pinion 69, meshing with a gear 70 on the hour-hand sleeve, which latter also carries a snail 39 of well-known construction.

On the rear face of the pinion 66 is formed a helical projection, constituting the let-off or striker-cam 42, on the helical face of which 10 trails a pin 43^a, projecting from the end of an arm 43^c of a lever 43, pivoted on a vertical pin in a stud 43^a, secured to the front face of the forward frame-plate 3, the arm 43^b of said lever being bifurcated and straddling the forward end of an arbor 47, which has endwise motion in its bearings in the frame-plates 3 and 4, said arbor having a collar, which forms an abutment for one end of a spring 46, coiled about the arbor, the opposite end of which 20 spring has bearing on the rear face of the forward frame-plate and tends to hold the arbor in a normally-retracted position.

To the outer end of arbor 47 is secured a lever 40, which has bearing on the bifurcated end of lever 43, said lever 40 having a toothed segment 40^a at its free end, adapted to gear with the pinion 48 on arbor 5, hereinabove referred to, said lever 40 being also provided with a weighted arm 41, Figs. 1, 5, and 6.

30 To the lever 40 is secured a contact-pin 55, adapted to trail over a segmental contact 54, secured to, but insulated from, the forward frame-plate 3, said contact-plate 54 having a hole, in which is secured an insulating-sleeve 35 57 for the reception of said contact-pin when the lever 40 is in a normal retracted position, said parts constituting the time-circuit closer.

From what has been said it will be seen that the lever 40, under the stress of its spring 46 40 on arbor 47, draws the bifurcated arm 43^b toward the forward frame-plate 3, and consequently holds the arm 43^c of said lever 43 away from said plate, and the pin 43^a on said lever-arm 43^c against the helical face of cam 42, as shown in Fig. 3. Above the arbor 47 and on the snail side of lever 40 is arranged an arbor 44, which also has endwise motion in its bearings in the frame-plates 3 and 4 and carries a collar that forms an abutment 50 for one end of a spring 44^a, whose opposite end has bearing on the front face of rear frame-plate 4 and tends to hold said arbor projected forwardly in the path of lever 40 and acts as a stop therefor.

55 To the rear end of arbor 44, back of the rear frame-plate 4, is secured a radial arm 49, bifurcated at its free end and straddling a sleeve 70^x, loose on a stub-arbor 71, projecting from the rear face of the frame-plate 4. To the 60 sleeve 70^x is secured a radial arm 72, adapted to be moved into the path of the hammer-lifting pins 50^a, projecting from the front face of disk 50 on arbor 5, hereinbefore referred to and as more clearly shown in Figs. 11 and 12. 65 On stub-arbor 71 is loosely mounted a sleeve 53^a, to which are secured the hammer-rod 53

and an arm 51, that projects forwardly over the lifter-arm 72 on sleeve 70^x.

As hereinabove stated and as more clearly shown in Figs. 11 to 13, the lever 43 carries 70 a pin 43^a on its arm 43^c, which pin is held against the cam or helical face of the let-off cam 42 by the stress of the spring 46 on arbor 47 acting on lever 40 to draw the same inwardly or toward the front frame-plate 3. As 75 said cam revolves, the lever 43, whose bifurcated arm 43^b straddles the arbor 47 in rear of lever 40, gradually draws the latter forwardly against the stress of the spring 46 until the aforesaid pin 43^a has reached the widest 80 part of the helical face of the let-off cam 42 and is about to drop onto its narrowest part. At this moment the contact-pin 55 has cleared 85 its insulating-sleeve 57, and the lever 40, which acts as a circuit-closer, swings toward the snail 39 until its weighted arm 41 comes to rest on one of the steps of the snail. After contact-pin 55 on lever 40 moves out of its sleeve 57 said lever will also be beyond or clear of the outer end of the arbor 44, and as soon as 90 the lever swings toward the snail the spring 46 on its arbor 47 draws said lever rearwardly, thereby moving the arbor 44 in a like direction against the stress of its spring 44^a. This rearward movement of the arbor 44 causes 95 the radial arm 49 thereon to move the sleeve 70^x in a like direction, thereby moving the hammer-lifting pin 72 into the path of the pins 50^a on disk 50, secured to arbor 5. Furthermore, as the lever 40 swings toward the 100 snail 39 and is during this movement drawn rearwardly by the spring 46, the toothed sector is brought into gear with the pinion 48 on the aforesaid arbor, while the contact-pin 55 is moved into contact with the segmental plate 105 54. At this moment the electric circuit is closed, the contact-pin 55 on lever 50 bearing on segmental contact 54, hereinabove referred to, and current from battery 13 will flow through wire 14, electromagnet 1, wire 15, electromagnet 1^a, wire 16 to column of mercury in circuit-breaker 17, wire 18, clock frame and mechanism, lever 40, contacts 55 54, and wire 56 back to battery 13. On the 110 closure of the electric circuit the electromagnets are energized and the armature 2 caused to make a partial revolution, which, as hereinbefore described, is transmitted to arbor 5 and to the hammer-actuating disk 50 thereon, 115 causing the hammer 52 to strike and at the same time partially winding up the motor-spring 20. As the armature oscillates, its arm 33 acts upon arm 32^b of the circuit-breaker to 120 interrupt the circuit, as before described, the armature 2 swinging back and establishing the circuit again through the circuit-breaker, as hereinbefore explained, these operations being repeated so long as the pin 55 on lever 40 remains in contact with the contact-plate 54. It will, however, be observed that the 125 lever 40 is in gear with the pinion 48 during the described operations, so that at each par-

tial rotation of said arbor the lever will be moved a certain distance away from the snail, or toward its normal position, until it has cleared the arbor 44, at which moment the 5 contact-pin 55 on the lever will be in register with the sleeve-bearing 57 in contact 54, thus allowing the spring 46 to retract the lever, while the arbor 44 is projected forwardly, thereby moving the sleeve 70 through the arm

- 50 5 o 49 in a like direction and withdrawing the radial arm 72 from the path of the lifter-pins 50^a on disk 50, the parts being again in their normal position, as hereinbefore described.

It is obvious that the number of strokes of 15 the hammer 52 will depend upon the length of time the contact-pin 55 remains in contact with the contact-plate 54, and it is further obvious that this is determined by the snail 39, since the greater the amplitude of the 20 throw of lever 40 toward said snail the longer will said contacts remain in contact.

To the hammer-rod 53 and to the rear frame-plate 4 are secured the opposite ends of a 25 spring 80, (see Figs. 4, 5, 6, 11, and 12,) which spring tends to draw said rod down to the sounding-spring 60, so that as said rod is lifted by the pins 50^a on disk 50 and again released the spring 80 acts to suddenly draw the rod down onto said sounding-spring 60, thus materially increasing the force of the 30 blow. In order that the hammer may not remain in contact with the sounding-spring after delivering a blow, and thereby damp or muffle the sound, I provide a resilient stop

35 81, projecting from the rear face of the back frame-plate 4 under said hammer-rod, which stop 81 yields under the blow of the hammer, but immediately recovering holds said hammer clear of the sounding-spring 60. (See 40 Figs. 11 and 12.)

To avoid injury to the contacts 54 55 through 45 sparking whenever the pin 55 is moved over the sleeve 57, I provide a shunt-circuit, through which the main circuit is kept closed through the medium of an auxiliary-circuit closer until the parts have returned into their normal positions.

To the front face of the forward frame-plate 3 is secured, but insulated therefrom, a 50 conductive plate 58, which carries a contact-spring 73 in the path of the rod 33 on the arm 2^a of the armature, Fig. 1, so that as said arm swings over to act upon arm 32^b of the circuit-breaker to interrupt the circuit the 55 shunt-circuit will be momentarily closed into the main circuit through said arm 33, the current flowing from battery 13 through wire 14, electromagnets 1 1^a, wire 16, circuit-breaker, wire 18, clock frame and mechanism, armature-rod 33, spring 73, plate 58, and wire 59 back to battery, thus maintaining the main circuit closed through the shunt-circuit during the short space of time required for the armature-rod 33 to swing over and act upon 60 arm 32^b of the circuit-breaker to interrupt the circuit, so that sparking at the contacts 54 55 will be avoided.

It will be observed that in the construction described the main time-arbor 64, which carries the minute and hour hand sleeves geared together, also carries the let-off cam (on the minute-hand sleeve) and the snail, (on the hour-hand sleeve,) whereby the clock mechanism is materially simplified, in that the number of its operative elements is greatly 75 reduced.

Having thus described my invention, what I claim as new therein, and desire to secure by Letters Patent, is—

1. The combination with the time-train of a 80 clock, its let-off cam and motor-spring, of a striking mechanism controlled by said let-off cam, said striking mechanism organized to partly wind up the time-train spring at each blow struck by the hammer of said striking 85 mechanism, for the purpose set forth.

2. The combination with a time striking mechanism, an electromagnet, its armature, a primary-circuit breaker, a secondary-circuit closer, a suitable electric circuit including 90 said electromagnet, circuit-breaker and circuit-closer, and means operated by the armature and operating the circuit-breaker and striking mechanism; of revoluble devices for controlling the operation of the circuit-closer, 95 a motor-spring for said devices, means for partially winding said spring at each blow struck by the hammer of the striking mechanism, and means for preventing overwinding of said motor-spring, substantially as set 100 forth.

3. The combination with the time-train and striking mechanism of a clock, and the motor-spring for said time-train; of electrically-controlled appliances for operating the striking 105 mechanism organized to partly wind said motor-spring at each revolution of the escape-ment-wheel and at each blow struck by the hammer of the striking mechanism, substantially as set forth. 110

4. The combination with the time-train and striking mechanism of a clock and the motor-spring for said time-train; of electrically-controlled appliances for operating the striking mechanism organized to partly wind said motor-spring at each revolution of the escape-ment-wheel and at each blow struck by the hammer of the striking mechanism, and means for preventing overwinding of the 115 spring, substantially as set forth. 120

5. The combination with the time mechanism of a clock, its actuating-spring, a winding mechanism therefor, a contact on the escape-ment-wheel and a resilient contact on but insulated from the anchor-arbor in the path of 125 the one on the escapement-wheel; of a pair of electromagnets, an oscillating armature therefor mounted loosely on the spring-winding-up arbor, means for transmitting the partial rotary movements in one direction of said armature to said winding-arbor, a suitable electric circuit including the electromagnets, the anchor-arbor contact and the clock mechanism, a primary-circuit breaker included in said 130

circuit operated by the armature to open the circuit as it oscillates in one direction under magnetic attraction when said circuit is closed through the escapement-circuit closer and to 5 again open the said circuit through the primary - circuit breaker when said armature swings back to a normal position, for the purposes set forth.

6. The combination of the winding-up arbor, a barrel loosely mounted thereon, the time-mechanism-actuating spring coiled on said barrel and the power-transmitting gear also loose on said arbor, said spring having one terminal secured to said barrel and the 15 other to said transmitting-gear; of a friction-coupling for coupling the barrel to the arbor, for the purpose set forth.

7. The combination with the time mechanism of a clock, its actuating-spring, a winding-arbor, a barrel loosely mounted thereon on which said spring is coiled, one end of which is secured to said barrel and the other to the power-transmitting gear; of said time mechanism, and a friction-coupling coupling 25 said barrel to said arbor; of electrically-controlled appliances operating to impart a partial rotation to the winding-up arbor (at each revolution of the escapement) in one and the same direction, for the purpose set forth.

8. The combination with the time mechanism of a clock, its actuating-spring, a winding-up arbor for said spring, electrically-operated appliances for imparting to said arbor periodical partial rotary movements in one 35 and the same direction, and a suitable electric circuit including said appliances and the clock mechanism; of a circuit-closer consisting of a contact-pin on the escapement-wheel, and a contact spring or springs projecting 40 from a sleeve on, but insulated from the anchor-arbor, into the path of the aforesaid pin, said sleeve included in the aforesaid electric circuit and said contacts arranged to close the circuit during one of the temporary stops 45 of the escapement-wheel, a primary-circuit breaker interposed in said circuit, means for operating the same during said temporary stop of the escapement to open the circuit, and means for subsequently reclosing said 50 circuit through the primary-circuit breaker, for the purpose set forth.

9. The combination with the bifurcated lever 32 on the arbor of the circuit-breaker 17, the electromagnets 1 and 1^a, a suitable electric circuit including said magnets, the arbor 5, the armature 2 thereon provided with an arm 33 extending between the arms of the aforesaid bifurcated lever, said armature carrying the toothed sector 37, of the arbor 38^a, 60 the pinion 38^b and governor 38 thereon, said pinion in gear with the sector 37, substantially as and for the purpose set forth.

10. The combination with the time mechanism of a clock, its actuating-spring, a winding-up arbor for said spring, and mechanism 65 for revolving said arbor in one direction only, a let-off cam on the minute-hand sleeve and

a snail on the hour-hand sleeve of the main arbor of said time mechanism; of a striking mechanism, electrically-operated appliances 70 controlled by said cam and snail for operating said striking mechanism and for imparting a partial revolution to the aforesaid winding-up arbor at each blow struck by the hammer, for the purpose set forth.

11. The combination with the main arbor of the time mechanism of a clock, the minute and hour hand sleeves on said arbor, a let-off cam revolving with the minute-hand sleeve, a snail revolving with the hour-hand sleeve, a 80 striking mechanism, electrically-operated appliances for actuating the same, comprising a revoluble arbor, an armature loose thereon, and means for transmitting the oscillations of the armature to said arbor and revolving the same in one direction only, electromagnets for said armature and a suitable electric circuit; of means controlled by the let-off cam for alternately closing and opening the electric circuit to alternately revolve and stop 90 the rotation of the aforesaid arbor, and means controlled by the snail for regulating the number of closures of said electric circuit, for the purpose set forth.

12. The combination with the main arbor 95 of the time mechanism of a clock, the minute and hour hand sleeves on said arbor, a let-off cam revolving with the minute-hand sleeve, a snail revolving with the hour-hand sleeve, a striking mechanism, electrically-operated appliances for operating the same comprising a revoluble arbor, an armature loose thereon, and means for transmitting the oscillations of the armature to said arbor and revolving the same in one direction only, 100 electromagnets for said armature, and a suitable electric circuit; of a circuit-closer, consisting of a lever provided with a contact-pin, and a segmental contact-plate, means for holding said lever with its pin normally out 105 of contact with said plate, means controlled by the let-off cam for releasing said lever, means for moving the latter with its pin into contact with the contact-plate when released, the amplitude of the motion of the lever, 110 hence the time during which the circuit is closed, being controlled by the aforesaid snail, a circuit-breaker operated to interrupt 115 and again open the electric circuit at each oscillation of the armature, and means operated by the armature-arbor for returning the circuit-closing lever into its normal position, 120 for the purpose set forth.

13. The combination with the main arbor, 125 64, the minute and hour hand sleeves thereon, the let-off cam and snail revolving with said minute and hour hand sleeves respectively, the arbor 5, the pinion 48 on said arbor, the appliances for revolving said arbor 5, and the segmental contact 54 provided with the pin-bearing 57; of the lever 40 carrying contact-pin 55 and having weighted arm 41, the arbor 47 on which said lever is mounted, the retracting-spring thereon and the lever 43

actuated by the let-off cam and acting on lever 40 to move the same and its arbor against the stress of its spring, for the purpose set forth.

5 14. The combination with the main arbor 64, the minute and hour hand sleeves thereon, the let-off cam and snail revolving with said minute and hour hand sleeves respectively, the arbor 5 carrying the hammer-actuating 10 disk 50, the pinion 48, and the armature 2 loose thereon, means for transmitting the oscillations of said armature to its arbor to revolve the same in one direction only, electromagnets for said armature included in a 15 suitable electric circuit, the arbor 71 carrying the hammer-supporting sleeve 53^a and a sleeve 70^x both loose on said arbor, said sleeve 70^x provided with an arm 72 adapted to be moved into the path of the pins on the hammer-lifting disk 50, and said sleeve 53^a carrying a 20 arm 51 extending across said arm 72, the endwise-movable arbor 44, its arm 49 engaging sleeve 70^x, and the contact 54 included in the aforesaid electric circuit and having 25 insulated bearing-sleeve 57; of the circuit-closing lever 40 having toothed segment 40^a, a weighted arm 41 adapted to contact with the aforesaid snail, the retractable arbor 47 of said lever, and a contact-pin 54 normally 30 seated in the sleeve 57, and the lever 43 operated by let-off cam to disengage the pin 54 from its sleeve and allow the lever 40 to swing over toward the snail, substantially as and for the purpose set forth.

35 15. The combination with the striking mechanism of a clock, electrically-operated appliances for actuating said mechanism, a suitable electric circuit including said appliances, a circuit-closer controlled by the let-off cam 40 of the time mechanism, a circuit-breaker, and means for alternately operating said circuit-closer and circuit-breaker; of means for maintaining the electric circuit closed through the circuit-breaker when the circuit-closer is 45 about to interrupt said circuit and before the circuit-breaker is operated, for the purpose set forth.

16. The combination with the striking mechanism of a clock, electrically-operated appliances for actuating said mechanism, a suitable electric circuit including said appliances, a circuit-closer controlled by the let-off cam of the time mechanism, a circuit-breaker, and means for alternately operating said circuit-closer and circuit-breaker; of a shunt-circuit 50 and means for closing said shunt-circuit into the main circuit through the circuit-breaker as the circuit-closer interrupts said main circuit and before the circuit-breaker is moved 55 to interrupt the same, for the purpose set forth.

17. The combination with the striking mechanism of a clock, electrically-operated appliances for actuating said mechanism, a suitable electric circuit including said appliances, a circuit-closer controlled by the let-off cam of the time mechanism, a circuit-breaker, and

means for alternately operating said circuit-closer and circuit-breaker; of a shunt-circuit and electrically-operated means for closing 70 said shunt-circuit into the main circuit through the circuit-breaker as the circuit-closer interrupts said main circuit and before the circuit-breaker is moved to interrupt the same, for the purpose set forth.

18. The combination with the let-off cam 42, snail 39, lever 43, arbor 5 carrying pinion 48 and hammer-actuating disk 50, the hammer-lifting pin 70 normally out of the path of the pins on said disk 50 and electrically-operated 80 mechanism for revolving arbor 5; of the circuit-closing lever 40 having toothed sector 85 40^a and contact-pin 55, the insulated contact-pin 54 having an insulated bearing for said pin 55, the arbor 47 to which said lever 40 is secured and which arbor is engaged by the lever 43, the retracting-spring for said arbor, the arbor 44 carrying the shifting lever 49 in engagement with the sleeve 70^x carrying the aforesaid hammer-lifting pin 72, the actuating-spring 44^a of said arbor 44, and a suitable 90 electric circuit including the contact-plate 54 and the appliances for revolving arbor 5, the recited parts being arranged and operating substantially as and for the purposes set 95 forth.

19. The combination with the striking mechanism of a clock, appliances for actuating said mechanism by successive electric impulses, a normally-open electric circuit and a 100 primary circuit making and breaking device in a normally-closed relation to said circuit; of a circuit-closer, a let-off cam, means actuated thereby and actuating the circuit-closer to periodically close the circuit, means for 105 determining the length of time said circuit shall remain closed, and means for operating the primary circuit maker and breaker to alternately open and close the circuit during the aforesaid period of closure, for the purpose set forth.

20. The combination with the striking mechanism of a clock, appliances for actuating said mechanism by successive electric impulses, a normally-open electric circuit and a 115 primary circuit making and breaking device in a normally-closed relation to said circuit; of a circuit-closer, a let-off cam, means actuated thereby and actuating the circuit-closer to periodically close the circuit, means for 120 determining the length of time said circuit shall remain closed, means for operating the primary circuit maker and breaker to alternately open and close the circuit during the aforesaid period of closure, and means for 125 moving the circuit-closer to again open the circuit at the expiration of said period of closure, for the purpose set forth.

21. The combination with the striking mechanism of a clock comprising a sounding device, a hammer, a hammer-actuating pin, a revoluble arbor, an oscillating armature, and a hammer-lifting-pin-actuating disk respectively loose and fast on said arbor, an elec-

tromagnet for said armature, a normally-open electric circuit, a primary circuit making and breaking device in a normally-closed relation to said circuit, and means for transmitting the oscillatory movements, in one direction, of the armature to its arbor; of a secondary-circuit closer, a let-off cam, means actuated thereby and operating the circuit-closer to periodically close the circuit, means for determining the period during which said circuit shall remain closed, and means controlled by the oscillations of the armature and operating the primary-circuit breaker to alternately open and close the electric circuit during such period of closure, substantially as and for the purpose set forth.

22. The combination with the striking mechanism of a clock, comprising a sounding device, a hammer, a hammer-actuating pin, a revolute arbor, an oscillating armature, a spring-barrel and a driving-gear loose thereon and a hammer-lifting-pin-actuating disk fast on said arbor, a motor-spring wound on the aforesaid barrel and having one end secured thereto and the other to said driving-gear, means for transmitting the oscillations, in one direction, of the armature to its arbor and to the spring-barrel, an electromagnet in a normally-open electric circuit, a circuit making and breaking device in a normally-closed relation to said circuit; of a circuit-closer, a let-off cam driven from the aforesaid gear on the armature-arbor, means actuated by said cam and operating the circuit-closer to periodically close the electric circuit, means for determining the length of time the circuit shall remain closed, means controlled by the oscillations of the armature and operating the aforementioned circuit making and breaking device to alternately open and close the circuit during said period of closure, and means controlled by the revolutions of the armature-arbor for moving the circuit-closer to again open the circuit after the expiration of said period of closure, for the purpose set forth.

23. The combination with the striking mechanism of a clock, comprising a sounding device, a hammer, a hammer-actuating pin, a revolute arbor, an oscillating armature, a spring-barrel and a driving-gear loose thereon and a hammer-lifting-pin-actuating disk fast on said arbor, a motor-spring wound on the aforesaid barrel and having one end secured thereto and the other to said driving-gear, means for transmitting the oscillations, in one direction, of the armature to its arbor and to the spring-barrel, an electromagnet in a normally-open electric circuit, a circuit making and breaking device in a normally-closed relation to said circuit; of a circuit-closer, a let-off cam driven from the aforesaid gear on the armature-arbor, means actuated from said cam and operating the circuit-closer to periodically close the electric circuit, means for determining the length of time the circuit shall remain closed, means controlled by the oscillations of the armature and operating the aforementioned circuit making and breaking device to alternately open and close the circuit during said period of closure and

means for moving the circuit-closer to again open the circuit at the expiration of said period of closure, for the purpose set forth. 70

24. The combination with the striking mechanism of a clock, comprising a sounding device, a hammer, a hammer-actuating pin, a revolute arbor, an oscillating armature, a spring-barrel and a driving-gear loose thereon, and a hammer-lifting-pin-actuating disk fast on said arbor, a motor-spring wound on the aforesaid barrel and having one end secured thereto and the other to said driving-gear, means for transmitting the oscillations, 75 in one direction, of the armature to its arbor and to the spring-barrel, an electromagnet in a normally-open electric circuit, a circuit making and breaking device in a normally-closed relation to said circuit; of a circuit-closer, a let-off cam driven from the aforesaid gear on the armature-arbor, means actuated by said cam and operating the circuit-closer to periodically close the electric circuit, means for determining the length of time the circuit 80 shall remain closed, means controlled by the oscillations of the armature and operating the aforementioned circuit making and breaking device to alternately open and close the circuit during said period of closure, and 85 means controlled by the revolutions of the armature-arbor for moving the circuit-closer to again open the circuit after the expiration of said period of closure, for the purpose set forth. 90

25. The combination with the striking mechanism of a clock comprising a sounding device, a hammer, a hammer-actuating pin, a revolute arbor, an oscillatory armature, a spring-barrel and a main driving gear-wheel 105 loose on said arbor, and a hammer-lifting-pin-actuating disk fast thereon, a mainspring wound on said barrel and having one end secured thereto and the other to said gear-wheel, means for transmitting the oscillations, in one direction, of the armature to its arbor and to the spring-barrel, an electromagnet in a normally-open main circuit, a circuit making and breaking device in a normally-closed relation to said main circuit, 110 and a circuit-closer in said main circuit; of a branch circuit, a circuit-closer therein, the time mechanism of the clock driven from the aforesaid mainspring, a let-off cam, and means actuated thereby and operating the 115 circuit-closer to periodically close the branch circuit through said main circuit, means for determining the length of time said branch circuit shall remain closed, means controlled by the oscillations of the armature and operating the aforesaid circuit making and breaking device to alternately open and close the main circuit and therethrough said branch circuit, means controlled by the armature-arm for moving the circuit-closer to again 120 interrupt the branch circuit at the expiration of the period of closure thereof, and a circuit-closer in the main circuit controlled by the clock-escapement to close said main cir- 125

cuit at every revolution of the escapement-wheel, substantially as and for the purpose set forth.

26. The combination with the striking mechanism of a clock comprising a sounding device, a hammer, a hammer-actuating pin, a revoluble arbor, an oscillatory armature, a spring-barrel and a main driving gear-wheel loose on said arbor, and a hammer-lifting-pin-actuating disk fast thereon, a mainspring wound on said barrel and having one end secured thereto and the other to said gear-wheel, means for transmitting the oscillations, in one direction, of the armature to its arbor and to the spring-barrel, means for permitting said arbor under certain conditions to revolve independently of said barrel, an electromagnet in a normally-open main circuit, a circuit making and breaking device in a normally-closed relation to said main circuit, and a circuit-closer in said main circuit; of a branch circuit, a circuit-closer therein, the time mechanism of the clock driven from the aforesaid main spring, a let-off cam, and means actuated thereby and op-

erating the circuit-closer to periodically close the branch circuit through said main circuit, means for determining the length of time said branch circuit shall remain closed, means controlled by the oscillations of the armature and operating the aforesaid circuit making and breaking devices to alternately open and close the main circuit and therethrough said branch circuit, means controlled by the armature-arm for moving the circuit-closer to again interrupt the branch circuit at the expiration of the period of closure thereof, and a circuit-closer in the main circuit controlled by the clock-escapement to close said main circuit at every revolution of the escapement-wheel, substantially as and for the purpose set forth.

In testimony that I claim the foregoing as my invention I have signed my name in presence of two subscribing witnesses.

HJALMAR EMANUEL ANDERSSON.
